(57) CLAIM

The ornamental design for an ophthalmologic apparatus, as shown and described.

DESCRIPTION

This application is related to U.S. design application Ser. No. 29/600,176 entitled "Cassette for Ophthalmologic Apparatus" that claims the same priority.

This application is related to U.S. design application Ser. No. 29/600,184 entitled "Pedal for Ophthalmologic Apparatus".

The contents of these three related applications are incorporated herein by reference in their respective entireties.

FIG. 1 is a right-front perspective view of an ophthalmologic apparatus in accordance with the present invention.

FIG. 2 is a right-rear perspective view of the apparatus.

FIG. 3 is a left-rear perspective view of the apparatus.

FIG. 4 is a left-front perspective view of the apparatus.

FIG. 5 is a left elevation view of the apparatus.

FIG. 6 is a front elevation view of the apparatus.

FIG. 7 is a right elevation view of the apparatus.

FIG. 8 is a rear elevation view of the apparatus.

FIG. 9 is a top view of the apparatus.

FIG. 10 is a rear perspective view of the apparatus with the tray dismounted and the display in an alternative position.

FIG. 11 is a rear perspective view of the apparatus with the tray dismounted and the lid of the container open.

FIG. 12 is a rear perspective view of the apparatus with the tray dismounted and the display in another alternative position.

FIG. 13 is a right-front perspective view of the apparatus with the tray in another alternative position.

FIG. 14 is a left-front perspective view of the apparatus with the tray in another alternative position; and,

FIG. 15 is a left-front perspective view of the apparatus with the tray in another alternative position.

The broken lines depict portions of the ophthalmologic apparatus that form no part of the claimed design.
